UNITED STATES PATENT OFFICE.

GABRIL SAMBOLL, OF ST. CLOUD, MINNESOTA.

GASOLENE-FUNNEL.

1,350,184.

Specification of Letters Patent. Patented Aug. 17, 1920.

Application filed March 4, 1920. Serial No. 363,163.

To all whom it may concern:

Be it known that I, GABRIL SAMBOLL, a citizen of Poland, residing at St. Cloud, in the county of Stearns and State of Minnesota, have invented certain new and useful Improvements in Gasolene-Funnels, of which the following is a specification.

This invention relates to certain new and useful improvements in gasolene funnels and has for its primary object to provide a ground receptacle within the funnel for the collection of sediment and a precipitation of water in the gasolene before the gasolene is discharged from the funnel into a receptacle.

A further object of the invention is to provide a gasolene funnel with a centrally positioned gasolene receiving tube having a closed bottom and lateral outlets that are adapted to diffuse the gasolene entering the funnel and also to assist in the separation of sediment and water from the gasolene while passing through the funnel.

With the above general objects in view, and others that will become apparent as the nature of the invention is better understood, the same consists in the novel form, combination and arrangement of parts herein fully described and shown in the accompanying drawings, wherein like reference characters designate similar parts throughout the several views.

In the drawings,

Figure 1 is a side elevational view partly broken away of a gasolene funnel constructed in accordance with the present invention.

Fig. 2 is a vertical cross sectional view taken on line II—II of Fig. 1 showing the interior construction of the funnel.

Fig. 3 is a top plan view of the funnel with the handle broken away.

Fig. 4 is a side elevational view of the gasolene receiving tube removed from the funnel and

Fig. 5 is a horizontal cross sectional view taken on line V—V of Fig. 4.

Referring more in detail to the accompanying drawings, there is illustrated a funnel especially designed for directing the flow of gasolene into a tank or other receptacle and embodies a cylindrical body portion 6 open at its upper end and having a conical extension 7 carried by the lower end thereof which conical extension terminates in an outlet mouth-piece 8, a handle 9 be-

ing secured to the exterior face of the funnel parts 6 and 7 as shown in Fig. 1 by which the same may be manipulated.

As shown more clearly in Fig. 2, a water drain and sediment collection receptacle 10 is centrally positioned within the funnel body and carries at its lower end an elbow pipe 11 that extends through the lower conical extension 7 of the body and is provided with a drain cock 12 for controlling the outlet of the receptacle 10, the elbow pipe 11 forming a support for the receptacle 10 within the funnel body. An overflow spout 13 is carried by the side wall of the receptacle 10 at a point spaced upwardly from the bottom of said receptacle and is adapted to discharge into the conical base 7 of the funnel body at a point above the screen completely covering the space between the funnel part 7 and the receptacle 10.

A gasolene receiving tube of the form best illustrated in Figs. 2 and 4 is supported upon the upper end of the receptacle 10 and embodies a double conical member including an upwardly flaring section 15 and an integral downwardly flaring section 16, spring arms 17 being carried by the section 15 with the free hooked ends thereof received over the upper edge of the section 15 for centrally supporting the gasolene receiving tube within said receptacle. A bottom 18 substantially of triangular formation as illustrated in Fig. 5 is received within the lower end of the conical section 16 while lateral outlets 19 are provided in the lower edge of the section 16.

In the use of the funnel above described, gasolene is poured into the receiving tube embodying the conical sections 15 and 16, and such gasolene flowing upon the bottom 18 will be partially broken and diffused and directed through the lateral openings 19 in the conical section 15 to feed the lower end of the receptacle 10. Sediment and water or other foreign matter in the gasolene will fall to the bottom of the receptacle 10 and seek a level in the elbow pipe 11 while the gasolene upon the surface thereof will flow through the receptacle spout 13 onto the screen 14 for further straining and finally to the outlet mouth 8 of the funnel. After a complete supply of gasolene has passed through the funnel, the funnel is removed from the receiving receptacle and the gasolene, water and other foreign matter in the lower end of the receptacle 10 and elbow

pipe 11 is emptied therefrom by opening the drain cup 12.

While there is herein shown and described the preferred embodiment of the invention, it is nevertheless to be understood that minor changes may be made in the novel form, combination and arrangement of parts without departing from the spirit and scope of the invention as claimed.

10 10. What is claimed as new is:

1. A gasoline funnel comprising a body portion, a receptacle centrally disposed within the body portion, an elbow pipe extending from the bottom of said receptacle through the side of said body portion, an outlet spout for said receptacle extending into the funnel body and means within said receptacle for directing the flow of gasoline entering the same.

20 2. A gasoline funnel comprising a body portion, a receptacle centrally disposed within the body portion, an elbow pipe extending from the bottom of said receptacle through the side of said body portion, an outlet spout for said receptacle extending into the funnel body, means within said receptacle for directing the flow of gasoline entering the same, said means comprising a tubular section suspended upon the upper edge of said receptacle.

30 3. A gasoline funnel comprising a body portion, a receptacle centrally disposed within the body portion, an elbow pipe extending from the bottom of said receptacle through the side of said body portion, an outlet spout for said receptacle extending into the

funnel body, means within said receptacle for directing the flow of gasoline entering the same, said means comprising a tubular section suspended upon the upper edge of 40 said receptacle, and open at its upper end, a plate closing the lower end of said tubular member, and lateral openings in the lower end of said member above said plate.

4. A gasoline funnel comprising a body 45 portion, a receptacle centrally disposed within the body portion, an elbow pipe extending from the bottom of said receptacle through the side of said body portion, an outlet spout for said receptacle extending into the funnel body, means within said receptacle for directing the flow of gasoline entering the same, said means comprising a tubular member suspended within the receptacle and means at the lower end of said tubular member 50 for diverting the flow of gasoline passing therethrough.

5. A gasoline funnel comprising a body portion, a receptacle centrally disposed within the body portion, an elbow pipe extending from the bottom of said receptacle through the side of said body portion, an outlet spout for said receptacle extending into the funnel body, means within said receptacle for directing the flow of gasoline 60 entering the same, and a screen extending between said receptacle and funnel body at a point below the outlet spout of said receptacle.

In testimony whereof I affix my signature. 70

GABRIL SAMBOLL.
